JOHN JACOB HERBERT, OF PHILADELPHIA, PENNSYLVANIA.

Letters Patent No. 103,880, dated June 7, 1870.

IMPROVEMENT IN LOOMS.

The Schedule referred to in these Letters Patent and making part of the same.

To all whom it may concern:

Be it known that I, JOHN JACOB HERBERT, of the city of Philadelphia, in the State of Pennsylvania, have invented a new and useful Improvement in Looms; and I do hereby declare the following to be a full, clear, and exact description thereof, which will enable others skilled in the art to which it appertains to make and use my improvement, reference being had to the accompanying drawing which form a part of this specification, and in which—

Figure 1 is a perspective view of the frame-work of my improved loom, showing the driving-gear, the mechanism which actuates the lathe, the improved take-up, and the registering apparatus.

Figure 2 is a sectional view of the cloth-beam, pressing-roller, and sand-paper roller, with the stuff passing over them.

Figure 3 is a perspective view of the mechanism which actuates the heddles, the cams and levers for driving the shuttles, the spooling apparatus, and warp-beam.

The same parts are denoted by the same letters in all the figures.

A is the driving-gear, to which motion is imparted in any suitable manner, and by which the pinion B, wheel C, shafts D E, and cams F F' are revolved.

The crank-wheel G on the shaft D is constructed with a slot, in which the pitman H is adjustable by means of a set-screw.

To the pitman is pivoted the vibrating arm I, connected, by the adjustable link K, to the vibrating arm L, to which is pivoted the pawl M, which takes into the ratchet-wheel N, as does also the pawl O, pivoted to the frame-work of the loom.

The pinion P on the shaft of ratchet-wheel N meshes into wheel Q, on whose shaft R are mounted the sand-paper roller S and the wheel T meshing into wheel U. The latter meshes into wheel V, on whose shaft W is loosely mounted the cloth-beam X.

Y is a roller to press the stuff against roller S as it passes to the beam X.

The beam X is provided with lugs a a, in each of which works an adjusting-screw, b, regulating the tension of the spring c, by which the clamp d is pressed against the shaft W. The beam X is thus clamped to the shaft W so as to revolve with it, while, at the same time, it is free to slip around the shaft whenever its rotation is resisted by a force greater than that of the springs c c.

The speed of the take-up may be varied by adjusting the pitman H and link K as the arm L is vibrated.

By the revolution of the crank-wheel G the pawl M rotates ratchet-wheel N, which is prevented from slipping back by pawl O. The revolution of the driving-gear thus imparts an intermittent motion to the take-up.

On the shaft E are mounted the cams A' A', B' B', and C' C', which actuate the treadles D' D', E' E', and F' F'.

The treadles F' F' are connected, by wires, to the heddle-levers G' G' G' G', and the treadles E' E' are similarly connected to the heddle-levers H' H' H' H'.

The lower heddle-levers H' H' H' H' are connected, by wires, to the upper heddle-levers I' I' K' K', from the other ends of which heddles 1 and 2 are suspended by wires, while the lower heddle-levers G' G' G' G' are similarly connected to the upper heddle-levers L' L' M' M', from which are suspended heddles 3 and 4.

Heddles 1 and 3 are connected on both sides by cords, which pass under pulleys N' N', and heddles 2 and 4 are similarly connected by cords, which pass under pulleys O' O'. These pulleys are connected to coiled springs, which are fastened to the floor or lower frame of the loom.

The rotation of shaft E depresses the treadles by means of the cams. When one pair of treadles is depressed the lower heddle-levers to which that pair is attached are also depressed, actuating the upper heddle-levers attached to them, and thereby raising one pair of heddles.

The elevation of one pair of heddles depresses the other pair by means of the cords which pass under the pulleys, and the depression of this latter pair actuates the upper heddle-levers, from which they are suspended, and thereby elevates the corresponding lower heddle-levers and the treadles attached thereto. The tension of the springs assists the movement of the heddles.

What I claim as my invention, and desire to secure by Letters Patent, is—

1. The cloth-beam, mounted on a rotating shaft, and held thereto by the adjustable spring-clamps, substantially as described.

2. The combination, with a heddle-frame, of pivoted levers I' K' above the frame, and connected, as described, to pivoted arms H' H' below the frame, and operated by treadles, all arranged and operating as set forth.

JOHN JACOB HERBERT.
